UNITED STATES PATENT OFFICE.

ANDREW SMITH, OF MILWAUKEE, WISCONSIN, ASSIGNOR TO SMITH LABORATORIES, INC., OF MILWAUKEE, WISCONSIN, A CORPORATION.

OILING SYSTEM FOR INTERNAL-COMBUSTION ENGINES.

Application filed October 6, 1924. Serial No. 741,990.

My invention relates to improvements in internal combustion engines and has special reference to the lubricating oiling systems thereof.

5 My object is to provide simple means for effectively removing the grit and other foreign matter from the lubricating and thus preserve the wearing surfaces of the engine.

10 My present invention is related to my invention described and claimed in my earlier application filed September 11, 1924, Serial Number 737,128.

15 In said earlier application I have shown and described a settling chamber below and in communication with the oil pan of the engine, a valve for closing off the communication when the engine is running and for opening up such communication when the engine is not running. In said earlier application the communication is closed by the 20 flow of oil set up in the pan by the fly wheel which dips into the oil.

25 In this present application the communication is closed by means of the vacuum pressure set up in some part of the engine, such as the vacuum tank, the intake manifold or some other suitable part.

30 My invention will be more readily understood by reference to the accompanying drawings forming part of this specification and in which:

35 Figure 1, is a transverse, vertical, central, sectional view of the oil pan of an internal combustion engine and provided with means for removing the grit, etc., embodying my invention in one form;

Figure 2, is a fragmentary plan view of the pan, shown in Figure 1;

40 Figures 3 and 4, are fragmentary, vertical, sectional views on the lines 3—3 and 4—4 respectively of Figure 1;

Figure 5, is a fragmentary plan view of one end of one of the valve blades or members;

45 Figure 6, is a vertical, central longitudinal section on the line 6—6 of Figure 2;

Figure 7, is a sectional view similar to Figure 6 and illustrating a modified form of my invention;

50 Figure 8, is a section similar to Figure 1 and taken on the line 8—8 of Figure 7;

Figure 9, is a fragmentary enlarged vertical sectional view on the line 9—9 of Figure 7;

Figure 10, is a fragmentary, horizontal 55 sectional view on the line 10—10 of Figure 9;

Fig. 11, is a fragmentary, horizontal sectional view on the line 11—11 of Figure 9;

Figure 12^a, is a detail fragmentary vertical section on the line 12^a—12^a of Figure 10;

Figure 12, is a fragmentary plan view of the pan portion of the crank case of an internal combustion engine equipped with a valve mechanism embodying my invention in 60 one form;

Figure 13, is a fragmentary longitudinal, central, vertical section on the line 13—13 of Figure 12;

Figure 14, is a vertical section on the line 70 14—14 of Figure 12; and

Figure 15, is an enlarged detail vertical section on the valve plate on the line 15—15 of Figure 12, especially showing the formed up shape of the valve plate between the opening therein.

In said drawings, 10 indicates a typical pan for closing the bottom of the crank case of an internal combustion engine. The bottom 11 of the pan is rounded transversely 80 and is preferably sloped longitudinally to a drain hole 12, normally closed by a screw plug 13. I arrange to close off the lower portion 14 of the pan when the engine is running and to open up communication between 85

this lower part and the pan proper when the engine is not running. It will of course be understood that the pan contains lubricating oil for the engine and that when the engine is running this oil is pumped up and delivered to the various bearings of the engine. When the engine is at rest the oil remains 90 stationary and all the matter contained in the oil, viz, grit, carbon, fibres, water, etc., settles to the bottom, at which time it can 95 settle down into the subsidiary chamber 14. As the engine starts the communication between this settling chamber or trap is closed and whatever has entered the settling chamber is held against rising again to mix with 100

the main body of oil, consequently the main body of oil is cleared of all deleterious matter every time the engine is at rest for a period long enough to permit such settling, practically one-half hour.

I am aware that many means can be provided for performing the function of closing and opening the communication, as above

mentioned, and I have shown and illustrated some practical arrangements in my said earlier application.

This present invention relates particularly to a valve mechanism for the purpose mentioned which is operable by the vacuum produced in various parts of the engine, viz, the vacuum fuel feed tank, the intake manifold or other parts. In this particular form 10 of my invention I prefer to open up the substantially whole top of the settling chamber, and for this purpose I provide a plurality of slat valves 15 arranged in the form of an old fashioned slat blind, that is, the 15 slats 15 are parallel with each other and when brought into closed position, as shown in dotted lines, the slats form a continuous horizontal position between the lower chamber and the main oil chamber. When the 20 slats are relieved of closing pressure they swing open to inclined position, as shown in full lines in Figure 1. For this purpose the slats are formed with longitudinally extending trunnion or bearing projections 25 16, as best shown in Figure 5, and are offset slightly to one side to make the lower parts 17 slightly heavier than the upper parts 18. For mounting the slat valves in 30 position within the pan, I provide depending sheet metal holders 19 in the form of Z-shaped strips at the two ends of the pan. These strips are arranged with their two edge flanges 20 and 21 arranged vertically, and the joining web 22 inclined inwardly. 35 The upper flange 20 is riveted to the end of the pan and the lower flange 21 depends vertically and is provided with bearing openings 23 of a size to freely receive the bearing projections 16 of the slats. In assembling 40 the device the slats are first assembled with the support members, the whole is lowered down into the pan and the support members 19 secured in place. To complete the closure I provide fixed longitudinal closure strips 25 along the sides of the pan and on substantially a level with the end members 19. These closure strips 25 are riveted 45 at their upper edges to the side walls of the pan and they are inclined downwardly into the paths of the adjacent sides of two end slats. The upper edge 26 engages upon the upper surface of one of the members 25 and the lower edge 27 of the opposite end slat engages beneath the edge of the opposite 50 member 25 when the slats are swung to closing position, as indicated in dotted lines in Figure 1.

For swinging the slats to closing position when the engine is running, I provide a 60 hollow collapsible diaphragm 27 of well known form, the interior of which is connected by a pipe 28 with some part or chamber of the engine in which the pressure is below atmospheric pressure when the engine 65 is running. The vacuum feed tank and the

inlet manifold are typical of such parts or chambers. Upon the starting of the engine the air is exhausted from the diaphragm 27 and the same is made thinner, that is, it shortens longitudinally. I make use of the 70 movement thus produced to close the valves. Usually it is best to make use of a plurality of diaphragms and I have shown two thereof connected together for cumulative movement. For connecting the diaphragms for 75 valve operation, I provide a bell-crank 29 pivotally mounted at its heel at 30 upon a fixed bracket or support 31. The bell-crank is arranged with one arm 32 extending up 80 to meet a rod 33 extending transversely across the pan and connected with the diaphragms for endwise movement thereby. The arm 32 and the free end of the rod 33 are pivotally connected, as shown at 85 34. The other arm 35 of the bell-crank 29 extends horizontally and its free end 36 is located substantially midway between the sides of the pan. Upon this end 36 I hang a valve operator 37 in the form of a thin plate bar 90 which extends transversely of the valve slats and the lower edge 38 of which is straight. The operator is balanced on a pivot 39 secured in the end 36 of the arm 35 of the bell-crank 29, and is arranged when lifted, on account of the expansion of the diaphragms 95 when freed of the vacuum, to rest just in contact with the upper edges of the several slats when in inclined open position. When the operator is depressed by the collapsing of the diaphragms, due to the production of 100 a partial vacuum in the chamber to which the pipe 28 is connected the weight of the operator is sufficient to depress the upper parts of the slats and rotate them on their bearings to closed position. If the weight 105 of the bar 8 does not carry the valves down the pressure transmitted to the bar will force them down and close off communication between the main oil chamber and the settling chamber. As the slats are made of thin 110 metal to make them of light weight and as they are usually quite long, I stiffen them by forming a narrow depending longitudinal flange 39 on the lower edge of each slat and an upstanding similar flange 40 on the 115 upper edge of each slat. The upper flange 40 is preferably bent off at slightly less than a right angle, so that when the slats are in closed position the several upper flanges will stand substantially vertical, thus being presented in the best relation to the valve operator.

Referring specifically to the form of my invention illustrated in Figures 7 to 11 inclusive; the pan 41 is similar to the pan 10 in Figures 1 and 2, in that it is adapted to 125 form the lower part of the crank case of an internal combustion engine and to contain lubricating to be circulated to the bearings and wearing surfaces of the engine. In this 130

form instead of dividing off the lower part of the pan to form a settling chamber, I attach a chamber 42 to the bottom 43 of the pan. The bottom of the pan is provided 5 with an opening 44 for the attachment of the settling chamber 42. The chamber 42 is provided in its top with an internally threaded opening 45 and I provide a clamping member 46 provided with an externally 10 threaded nozzle 47 for engagement in the opening 45 and by means of which the two parts 42 and 46 can be clamped in position. In order to make the joint tight I interpose a soft packing washer 48 between 15 the top of the chamber 42 and the bottom of the pan, providing surfaces for properly receiving the washer. The clamping member 46 is provided with a large central opening 49 affording communication between 20 the pan and the settling chamber 42. It is this opening through which the sediment settles into the chamber 42, and it is this opening which I arrange means to close when the engine is running and to open 25 when the engine is not running.

For the purpose of providing means on the member 46 for engagement with the inner surface of the bottom of the pan for clamping the device to the pan and to avoid 30 any serious obstruction to the free movement of the sediment down along the inner surface of the pan into the sediment chamber, I provide radial projections 50 on the upper end of the threaded nozzle 47, the 35 metal between the projections being cut away down to the lower surfaces of the projections. This construction leaves the spaces between the projections free down flush with the inner surface of the bottom 43 for the 40 movement of the settled material down into the chamber 42.

For controlling the opening 49 I provide a light weight disk valve 51 arranged just 45 below the opening 49 and adapted to be lifted to seat against a circumferential valve seat 52 to close off communication with the settling chamber. Below the seat 52 the communicating opening is enlarged in diameter, as shown at 53, to afford ample flow 50 space around the edge of the valve 51. I provide several valve guide projections 54 within the enlarged opening 53. The valve head 51 is rigidly clamped upon a central stem 55 which rises into the pan and which 55 carries at its upper end one or more collapsible diaphragms 56, which are hollow and are connected by a pipe 57, communicating with some chamber or part of the engine in which a vacuum is maintained 60 when the engine is running. The upper diaphragm is rigidly clamped to a fixed bridge plate or member 58, so that when the diaphragms are collapsed the valve 51 is lifted into contact with its seat, and when they are 65 allowed to expand upon the cessation of the

vacuum the valve is lowered away from the seat. While the bridge plate 58 might be mounted in the pan in various ways, I prefer to secure it upon the tops of posts 59 rising from lugs 60 formed integrally with 70 the member 46, so that the various parts can be assembled together and mounted as a whole in the pan. The pipe 57 is connected with the vacuum chamber, preferably by a pipe 61, which passes out through the side 75 of the pan and is tightly clamped therein, as best shown in Figure 8.

In Figure 9, I have shown the valve in open position in full lines and in closed position in dotted lines and its operation will 80 be clear from the foregoing.

Referring now to the form of my invention illustrated in Figures 12 to 15; I have shown a form somewhat similar to that shown in Figures 1 to 5, in that I divide 85 off the lower portion 62 of the engine pan 63 by means of a fixed horizontal partition wall 64 which preferably extends throughout the whole area of the pan. This horizontal partition wall is perforated, the holes 90 65 thereof being spaced preferably about $\frac{3}{4}$ of an inch centers, and being preferably about $\frac{3}{8}$ of an inch in diameter, thus providing ample flow area to allow the sediment to drop into the divided off portion 95 of the pan.

For the purpose of closing off the lower portion 62 from the main part of the pan at times when the engine is running, I provide a second or top plate 66 which is likewise perforated and the holes 67 of which are adapted to be placed in registry with the holes 65 to afford communication and out of registry to close off communication. 100

While it is obvious that the plate 66, 105 which may aptly be called a valve, could be moved back and forth in many different ways, either manually or automatically, I prefer to provide simple means for moving it automatically. The means which I have shown consist of collapsible diaphragms 68, 110 similar to those already described in connection with the other forms of my invention. These diaphragms are hollow and are connected by a pipe 69 to any suitable chamber of the engine in which a pressure below atmosphere is produced when the engine is running. The diaphragms are operatively connected to the plate 66 by any suitable means, such as the rod 70, which connects at its free end with a swinging lever 71 pivotally mounted at its upper end 72 on a rod 73 which is fixed in brackets 73' and pivotally connected at its lower end 74 to a lug 75 115 fixed upon the top side of the plate valve 66. When the diaphragms are collapsed they pull the plate in one direction against a suitable stop 76, and in which position the openings in the lower plate are closed by the 120 upper plate. When the engine stops and 125 130

the diaphragms are freed of the vacuum action the valve plate is drawn back against a stop 77 at the other end, in which position the holes in the two plates are in registry and the sediment can flow down into the trap portion 62 of the pan. The plate can be drawn back by any suitable means, such as a tension spring 78 attached at one end to the plate 66 and at the other to the wall 10 of the pan. The plate 66 is guided in its back and forth movement by suitable guide clips 79. The bottom of the pan 63 is provided with a removable screw plug 80 by which the collected sediment can be removed 15 from time to time. The plate 66 is formed up between the openings 67 therein, as best shown in Figure 15 at 81, to eliminate all flat top surfaces upon which the sediment could lodge and accumulate. In other 20 words, the whole plate is freed of all sediment as soon as it is moved to open the holes leading into the sediment chamber, and any sediment which does settle down on the plate 66 between the holes 67 slides down the 25 inclined surfaces produced by forming up the plate between the holes 67, and falls through the openings into the sediment chamber.

As many modifications of my invention 30 will readily suggest themselves to one skilled in the art, I do not limit or confine my invention to the specific constructions or methods of operation herein shown and described.

35 I claim:

1. In an internal combustion engine, a crank chamber adapted to contain lubricating oil for the engine, a settling chamber below the crank chamber having communication with the crank chamber, valve means for closing off such communication, and means connected with a part of the engine in which the pressure is normally below atmospheric pressure, when the engine is 40 running, for closing said valve means at times when the engine is running, said valve means being adapted to automatically open again when the engine stops running.

2. In an internal combustion engine, a 45 crank chamber adapted to contain lubricating oil for the engine, a settling chamber below the crank chamber having communication with the crank chamber, a valve mechanism for closing off such communication, a hollow collapsible valve operator connected with a part of the engine in which the pressure is below atmosphere when the engine is 50 running and operably connected to a valve in said mechanism to close same when the engine is running, the said valve being adapted to open when relieved of the closing action of said operator.

3. In an internal combustion engine, a 55 crank chamber, a settling chamber below same, a passage affording communication between the two, a valve controlling said passage, and means operable by vacuum pressure for closing said valve, as and for the purpose specified.

4. In an internal combustion engine, a 60 crank chamber, a settling chamber below same, a passage affording communication between the two, a valve adapted to be lifted for closing said passage, a diaphragm collapsible by vacuum pressure and connected with the valve for closing same, the valve being adapted to open automatically when released from closing action of the diaphragm.

5. In an internal combustion engine, a 65 chamber in which lubricating oil for the engine is adapted to be agitated when the engine is running, a settling chamber below said agitation chamber, communication between the two chambers, a valve controlling said communication, and means controlled by a variation from the normal pressure which variation is produced by the engine when running, and is operative to close said valve when the engine is running and open the valve when the engine is not running.

6. In an internal combustion engine, a settling chamber normally in communication with the engine lubricating oil system when the engine is not running and pressure operable means subject to a pressure below atmosphere, produced by the engine, for closing off such communication when the engine is running.

7. In an internal combustion engine, having a lubricating oil system and a chamber for containing the oil, a settling chamber in communication with the oil chamber, a valve for closing off such communication, a hollow valve operator adapted to be collapsed by a pressure below atmosphere, produced by the engine when running, and operable thereby to hold said valve closed while the engine is running.

8. In an internal combustion engine having a crank chamber adapted to contain lubricating oil, a settling chamber below the crank chamber, communication between the two chambers, a valve adapted to be lifted to close off such communication, and pressure responsive means adapted to be operated by a pressure below atmosphere, produced by the engine when running, and connection between said means and said valve whereby said valve is lifted to close off said communication while the engine is running.

In testimony whereof, I have hereunto set my hand, this 25 day of September, 1924.

ANDREW SMITH.
